(57) **CLAIM**

The ornamental design for an eyewear brow bar, as shown and described.

DESCRIPTION

FIG. 1 is a top, front, right side perspective view of the eyewear brow bar according to our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dash-dash broken lines illustrate the environment and portions of the eyewear brow bar that form no part of the claimed design. The dot-dash broken lines represent boundaries of the claimed design and form no part of the claimed design.

1 Claim, 5 Drawing Sheets
